UNITED STATES PATENT OFFICE.

LEE S. LINES, OF CLEVELAND, OHIO, ASSIGNOR TO THE RUSS COMPANY, OF CLEVELAND, OHIO, A CORPORATION OF OHIO.

DESIGN FOR A DISPENSING-URN.

48,594.

Specification for Design.

Patented Feb. 22, 1916.

Application filed September 13, 1915. Serial No. 50,520. Term of patent 7 years.

To all whom it may concern:

Be it known that I, LEE S. LINES, a citizen of the United States, residing at Cleveland, in the county of Cuyahoga and State of Ohio, have invented a new, original, and ornamental Design for a Dispensing-Urn, of which the following is a specification, reference being had to the accompanying drawing, forming part thereof.

The figure is a perspective view of the design.

I claim:—

The ornamental design for a dispensing urn, as shown.

LEE S. LINES.
